UNITED STATES PATENT OFFICE.

CHARLES WILFRED BIRKIN AND EDWIN THOMAS SANDS, OF BROADWAY, NOTTINGHAM, ENGLAND, ASSIGNORS TO BIRKIN AND COMPANY, OF BROADWAY, NOTTINGHAM, ENGLAND.

DESIGN FOR LACE.

Application filed July 19, 1926. Serial No. 18,407. Term of patent 3½ years.

To all whom it may concern:

Be it known that we, CHARLES WILFRED BIRKIN and EDWIN THOMAS SANDS, subjects of the King of Great Britain, residing at Broadway, Nottingham, England, have invented a new and original ornamental Design for Lace, of which the following is a specification, reference being had to the accompanying drawing, forming part thereof. The drawing shows a portion of the lace.

We claim:

The ornamental design for lace substantially as shown.

CHARLES WILFRED BIRKIN.
EDWIN THOMAS SANDS.
